WEATHERPROOF METAL SASH

Irvin Nicholson and Francis Shields,
Selden, Kans.

Application May 18, 1934, Serial No. 726,358

6 Claims. (Cl. 189—69)

The object of our invention is to provide a novel and useful weatherproof steel basement sash of novel construction as hereinafter described. We attain the objects of our invention by the device illustrated in the accompanying drawings, in which,—

Figure 1 is a front plan view of the metal sash and frame viewed from the inside;

Fig. 2 is an edge elevation of same;

Fig. 3 is a longitudinal section on line 3—3 of Fig. 1;

Fig. 4 is a detail perspective view of a corner of the sash and frame illustrating the sash lock on an enlarged scale;

Fig. 5 is a plan view of the outside of the sash and frame;

Fig. 6 is a transverse section on line 6—6 of Fig. 5; and—

Fig. 7 is an end elevation with the sash in open position.

Like numerals designate like parts in each of the several views.

Referring to the accompanying drawings, we provide a metal window frame comprising the head jamb 1, sill 2, side jamb 3, and opposite side jamb 4. We provide suitable brick and tile stays 5 welded on the side jambs as shown in Fig. 3.

As shown in Fig. 6, the sill 2 is bent longitudinally at 6 and has the outwardly curved portion 7. We provide a curved weatherstrip 8 welded to sill 2 as shown in Fig. 6. We provide suitable hinges for hingedly mounting the window sash on the head jamb of the window frame. In the drawings, there are illustrated brackets 9 of head jamb 1, hinges 11, and brackets 10 in which the lower ends of hinges 11 are slidably mounted. We provide a coil spring 11a on hinges 11 disposed between the spaced brackets 10, the spring being secured to the hinge at the outer end by a suitable pin or the like to provide an efficient spring hinge. Hinges 11 are of T-shape as shown.

We provide a window sash comprising a metal top rail 12, metal bottom rail 13, metal end rails 14 and 15, and metal muntins 16. Members 12, 13, 14 and 15 are L-shaped in cross section.

We provide suitable guides 17 in which are slidably mounted suitable locking bolts or catches 18 pivotally attached at 22 to catch operating members 19 which in turn are pivotally mounted by member 21 on the sash rail 13. We provide apertures 23 in the side jambs 3 and 4 to receive the bolts 18 to lock the sash in closed position. We provide a suitable handle 24 for the sash.

As shown in Fig. 6, we provide a curved weatherstrip guard 25 extending longitudinally of the sash and forming the bottom thereof as shown in Fig. 6 and of similar curvature in cross section to the curvature of the weatherstrip 8 with which it snugly contacts when the sash is in closed position. We provide a suitable glass pane 27 which is held in place by putty 26 and other suitable means.

We provide a weatherstrip 28 depending from head jamb 1. We provide a screen 33 mounted in the screen frame members 29 and 31. Screen frame members 31 are fastened in place on V-shaped weatherstrips 30 by means of bolts 32, as shown in Figs. 3 and 5.

The weatherstrip extensions 30 have their ends slanted or beveled, as shown in Fig. 6, to allow the sides 25 and 34 of the window frame to seat snugly in place, as shown in Fig. 6 and Fig. 3, with members 25 and 8 in abutment and with said weatherstrip extensions 30 overlapping the end puttied portions 26 of the window frame, said puttied portions extending entirely around the window frame, as indicated in Fig. 3 which is a longitudinal section, and Fig. 6 which is a transverse section, whereby the V-shaped weatherstrip element 30 and the window frame and its puttied portion 26 cooperate in forming a weatherproof closure for the window opening.

The operation of the invention will be understood by referring to Figs. 1, 4, 6 and 7. The sash, which is intended for basement windows, is mounted on the spring hinges illustrated in Figs. 1 and 6 which is swingable inwardly as shown in Fig. 7. The screen 33 is permanently held in place by the frame members 31 and 29, the member 31 being bolted to the member 29 which latter member is also welded or affixed to the side jambs 3 and 4 of the window frame, by welding 31a, as shown in Fig. 3, at each end of the window frame. The V-shaped or turned weatherstrip extension 30 of member 29 seats snugly against the puttied portion 26 to seal the ends of the window frame from the entrance of rain. The depending weatherstrip 28, as shown in Fig. 6, which extends longitudinally of head jamb 1 and which is interposed between the screen frame member 29 and the top rail 12 of the sash frame, prevents entrance of water at the top of the sash. The curved weatherstrip 8 welded longitudinally of the sill 2 and on which the curved weatherstrip guard extending along the bottom of the window sash snugly seats forms an effective closure against the admission of water at the bottom of the window frame and window sash. The out-

wardly curved shape of the portion 7 of the sill tends to shed water.

The operation of the locking bolts or catches 18 which are positioned for engagement in the apertures 23 in the side jambs of the window opening will be obvious by reference to Fig. 4, which also clearly illustrates the pivoted cam or catch operating member 19. The window frame, as shown in Figs. 3 and 6 of the drawings, is substantially U-shaped in cross section.

As shown in Fig. 3, the side jambs 3 and 4 of the window frame are provided with brick and tile stays 5 which are used in securing the window frame in the wall of the building in which this 15 basement window sash is mounted.

What I claim is:

1. In a weatherproof metal sash, the combination of a sash frame L-shaped in cross section, a pane mounted in said sash frame, putty filling 23 the L-shaped portions of said sash frame securing said pane in the sash frame, a metal window frame within which the sash frame is hingedly mounted, weatherstrips V-shaped in cross section and welded on the sides to the window frame, said weatherstrips having their inner members seated snugly against the said putty to seal the ends of the window frame.

2. In a weatherproof metal sash, the combination of a sash frame L-shaped in cross section, a pane mounted in said sash frame, putty extending across the L-shaped ends of said sash frame securing said pane in the sash frame, a metal window frame within which the sash frame is hingedly mounted, a depending weatherstrip 30 welded on the head jamb of the window frame to make a weatherproof frame, weatherstrips V-shaped in cross section welded on the sides of the window frame and seating snugly against the aforesaid putty.

3. In a weatherproof metal sash, the combination of a sash frame L-shaped in cross section, and having muntins, a pane mounted in said sash frame, putty securing said pane in the sash frame and providing a diagonal outer surface, a metal window frame within which the sash frame is hingedly mounted, weatherstrips V-shaped in cross section welded on the sides of the window frame and having one of their members snugly seating on the surface of the putty to 35 seal the ends of the sash, a weatherstrip curved in cross section welded on the sill of the window

frame, and a weatherstrip guard forming the bottom portion of the window sash frame and of similar curvature in cross section to the weatherstrip on the sill to snugly contact therewith when the sash frame is in closed position.

5

4. In a weatherproof metal sash, the combination of a sash frame angular in cross section, a pane mounted in said sash frame, putty securing said pane in the sash frame, a metal window frame within which the sash frame is hingedly mounted, weatherstrips V-shaped in cross section and welded on the sides of the window frame and having one member snugly seating against the surface of the putty, and hinges mounted on the head jamb of the window frame and operatively connected with the frame of the window sash.

5. In a weatherproof metal sash, the combination of a sash frame, a pane mounted in said sash frame, putty securing said pane in the sash frame, a metal window frame within which the sash frame is hingedly mounted, weatherstrips V-shaped in cross section welded on the sides of the window frame and having one of the members seating snugly against the aforesaid putty to seal the ends of the sash frame, a weatherstrip depending from the head jamb of the window frame and interposed between the screen frame and the top rail of the window sash, and hinges mounted on the head jamb of the window frame and operatively connected with the frame of the window sash.

6. In a weatherproof metal sash, the combination of a sash frame, a pane mounted in said sash frame, means securing said pane in the sash frame, a metal window frame within which the sash is hingedly mounted, weatherstrips welded on the sides of the window frame snugly seating on the means securing the pane in the sash frame, a weatherstrip guard curved in cross section and forming the bottom portion of the window sash frame, a correspondingly curved weatherstrip welded on the sill of the window frame and cooperating with the aforesaid weatherstrip guard to effect a weatherproof close 45 sure, and hinges mounted on the head jamb of the window frame and operatively connected with the frame of the window sash.

FRANCIS SHIELDS. 50
IRVIN NICHOLSON.
